RAILWAY FLAT CAR UNDERFRAME

Jack E. Gutridge, Munster, Ind., assignor to Pullman-Standard Car Manufacturing Company, Chicago, Ill., a corporation of Delaware

Application January 27, 1954, Serial No. 406,429

2 Claims. (Cl. 105—414)

This invention relates to a railway flat car and more particularly to an underframe structure for a flat car specially constructed for transporting standard sized highway trailers or their equivalent.

Special devices used for the particular purpose of the flat car include holding devices for the rear of the trailers and vehicle stands movably attached to tracks affixed to the car flooring for holding the fifth wheel ends of the trailers, such holding devices and stands not being parts of the present invention.

The principal object of this invention is an underframe construction including novel structural arrangements providing sufficient strength to withstand the particular loads transmitted to it by the holding devices and vehicle stands when in use, and yet a construction which is light-weight, economically assembled, and of common stock material.

Another object of this invention is to provide supporting means between the car bolsters and the car ends in order to strengthen the resistance of the floor structure to bending moments placed thereon.

And yet another object of this invention is to provide novel supporting means between the car bolsters and closely adjacent the center sill for strengthening the floor structure adjacent thereto.

A further object of this invention is to provide novel floor stringer means in an underframe structure where the crossbearers undlie the center sill.

These and other objects will be more apparent from the description and drawings, in which:

Fig. 1 is a fragmentary top plan view of one end of a railway flat car;

Fig. 2 is a side elevational view of the portion of the car shown in Fig. 1;

Fig. 3 is a fragmentary top plan view of a central portion of the car;

Fig. 4 is a side elevational view of the central portion of the car shown in Fig. 3;

Fig. 5 is a fragmentary top plan view of the other end of the car;

Fig. 6 is a side elevational view of the portion of the car shown in Fig. 5;

Fig. 7 is a sectional view taken on the line 7—7 of Fig. 3;

Fig. 8 is a sectional view taken on the line 8—8 of Fig. 1 showing the internal structure at the car end;

Fig. 9 is a sectional view taken on the line 9—9 of Fig. 1 showing the underframe structure at a bolster;

Fig. 10 is a sectional view taken on the line 10—10 of Fig. 3 showing the underframe structure at a cross-bearer; and

Fig. 11 is a fragmentary end elevational view of the car portion shown in Fig. 1.

Referring to the drawings, a railway flat car is depicted having a floor 20 supported by side sills 21, body bolsters 22, and crossbearers 23, the car being supported at each end on a truck (shown in phantom). For purposes of clarity of disclosure, the car is arbi-

2

trarily divided into a front section 24 and a rear section 25 (Fig. 3). In order to hold or lock the rear of a standard-sized highway trailer, a first front holding device, generally indicated at 26, is attached to the car floor at the extreme front of the car, and a second holding device 27 is attached to the car floor 20 at the center of the car for holding another trailer.

For the purpose of supporting the front or fifth-wheel end of a trailer, a first vehicle stand 28 is provided to be used with the first device 26. To provide for varying trailer lengths, the stand 28 is movable longitudinally of the car on a track 29 which is secured to the car floor 20 and which is of a predetermined length, herein depicted as extending from the center device 27 toward the front device 26 for at least half the length of the front section 24. A second vehicle stand 30 is provided to be used with the center device 27, being movably mounted on a track 31 of predetermined length, herein depicted as extending from the car rear end wall 32 toward the center device 27.

Each bolster 22 comprises a pair of parallel, vertically disposed webs 33 and a pair of bottom plates 34 secured to the lower edges of the webs and extending from the center sill, generally indicated at 35, to the side sills 21. A pair of channel shaped stiffeners 36 extend across the top of the center sill to connect the web portions on opposite sides thereof (Fig. 8). A body center bearing plate unit 37 of the usual construction is attached beneath each bolster. As indicated herein, a longitudinally movable center sill unit 35 is provided, using a commercially available center cushioning means 38. Any suitable construction may be employed in the bolster between the laterally spaced portions 35a of the center sill to receive the king pin.

The front holding device 26 is secured to the car structure by means of a pair of side channels 39, a pair of vertical center channels 39a, and a rear panel 40, all secured to an end sill angle member 41 which, with a brace 26a, is secured to the floor 20. Due to the constant horizontal stresses placed on the device 26 by the attempted longitudinal movement of the attached trailer resulting from buffing and draft forces, a structurally stronger floor construction as compared to the usual floor arrangement is necessary in order to resist such forces transmitted to the floor in the form of bending or twisting components acting in opposite directions. For this purpose, a novel pair of support brackets 42 and 43 (Figs. 8 and 9) were conceived which strengthen the floor and the entire car end structure in a manner sufficient to withstand all expected bending moment stresses. Each bracket is comprised of a pair of parallel vertically disposed web plates 44 and 45 secured at their bottom edges to a base plate 46 perpendicular to the web plates. The base plate has a horizontal portion 47 and a downwardly extending portion 48, the latter portion being secured to the front edge 49 of the front bolster base plate 34 as by welding. A stiffening plate 50 is secured to the inner base portion of each base plate 46.

Both web plates 44 and 45 are shaped to fit against the adjacent floor, bolster, and plate surfaces in order that they may be secured thereto, as by welding, the inner plate 45 being shaped slightly differently than the outer plate 44 at the bolster end to accommodate the bolster front channel-shaped stiffener 36. A generally triangular end gusset plate 51, which is secured to the end sill angle 41 and the side sill 21 (Fig. 11) and connected to the end of each bracket 42 or 43 by a tie plate 52, completes the novel car end structure. As either car end, or possibly both, may have a holding device 26 secured thereto, the rear end of the car has the identical construction as the front end.

The crossbearers 23 are each comprised of a transversely extending I beam attached to the lower portion of the side sills 21 and extending completely across the car under the center sill, instead of the usual crossbearer arrangement being broken by the center sill. A novel floor supporting construction with respect to the longitudinally extending stringers is used between the body bolsters, comprising a pair of upwardly facing channel members 53 and 54, one on each side of the center sill (Fig. 10), and secured to the flooring 20. At each crossbearer 23, vertically disposed beam sections 55 are secured between the crossbearer and stringer to support the floor stringer channel members 53 and 54.

Longitudinal central support for the floor is provided by a pair of vertically extending L-shaped elements 56 and 57 (Figs. 1 and 10), located closely adjacent each side of the center sill 35 (Figs. 7 and 10), with their flanges extending outwardly. This supporting structure is necessary where the load forces are greatest, which may be at any point along the front track 29 and the rear track 31. Thus the supporting elements are divided into two portions. A front portion 58 extends under the front track 29 and rearwardly therefrom to the first crossbearer 23 of the rear car section 25 adjacent the holding device 27. The latter extension is necessary as the same bending moment problem as at the front holding device 26 exists at the center holding device 27. A rear portion 59 extends under the rear track 31 except from the bolster to the car end, as the support brackets 42 and 43 give sufficient support for that floor portion. At each crossbearer 23, a channel-shaped stiffener 60 is secured across the top of the center sill 35 to the inner top surface of each element 56 and 57. And at the free forward end of the element rear portion 59, a support spacer 61 (Figs. 5 and 6) is secured across the base of the elements.

Thus, a novel underframe construction is presented having a pair of brackets extending from each bolster to the adjacent end of the car and secured to the bolster and flooring for strengthening the floor structure so as to resist bending forces placed thereon. Also included in the construction is a pair of flanged supporting elements secured between the floor and the crossbearers and closely adjacent the center sill for supporting the floor centrally thereof and for stiffening the floor area adjacent a center trailer holding device. The two aforementioned novel features, plus a unique floor stringer arrangement, provide an underframe construction which has sufficient strength to withstand all loads placed there-

on due to the specific purpose for which the car is used, is capable of easy assembly, and is comprised of commercially available stock.

What is claimed is:

5. 1. In a railroad car for the purpose described having a floor and an underframe comprising a center sill, side sills, end sills, cross bearers, and body bolsters between the cross bearers and the end sills, the combination therewith of means supporting said floor on said underframe comprising a first set of members overlying the cross bearers and extending only between the bolsters and connected at their ends thereto and including a pair of members each having a vertical web located closely adjacent a side of the center sill and another pair of members each spaced equidistantly between the center sill and one of the side sills, the upper edges of each of said pairs of members being operatively connected to the floor for supporting the same, and said supporting means comprising also a second set of members including a pair of bracket assemblies extending from each bolster to the adjacent end sill, each bracket assembly being spaced laterally from the center sill and comprising a pair of laterally spaced vertical longitudinal plates having their inner ends connected to the adjacent bolster and their outer ends connected to the adjacent end sill, and a generally horizontally disposed base plate connecting the bottom edges of the plates of each pair, the upper edges of said bracket assemblies being operatively connected to the floor for supporting the same.
10. 2. The combination claimed in claim 1 in which the base plate of each bracket assembly has approximately one-half its length horizontally disposed and the remaining length angularly inclined downwardly therefrom and includes a flat stiffening plate secured to the bottom of
15. 3. The combination claimed in claim 1 in which the base plate of each bracket assembly has approximately one-half its length horizontally disposed and the remaining length angularly inclined downwardly therefrom and includes a flat stiffening plate secured to the bottom of
20. 4. The combination claimed in claim 1 in which the base plate of each bracket assembly has approximately one-half its length horizontally disposed and the remaining length angularly inclined downwardly therefrom and includes a flat stiffening plate secured to the bottom of
25. 5. The combination claimed in claim 1 in which the base plate of each bracket assembly has approximately one-half its length horizontally disposed and the remaining length angularly inclined downwardly therefrom and includes a flat stiffening plate secured to the bottom of
30. 6. The combination claimed in claim 1 in which the base plate of each bracket assembly has approximately one-half its length horizontally disposed and the remaining length angularly inclined downwardly therefrom and includes a flat stiffening plate secured to the bottom of
35. 7. The combination claimed in claim 1 in which the base plate of each bracket assembly has approximately one-half its length horizontally disposed and the remaining length angularly inclined downwardly therefrom and includes a flat stiffening plate secured to the bottom of
